United States Patent Office.

CHARLES J. SMITH, OF NORFOLK, VIRGINIA.

Letters Patent No. 101,322, dated March 29, 1870.

IMPROVEMENTS IN BOLTS FOR SAFETY-STOVES FOR CARS.

The Schedule referred to in these Letters Patent and making part of the same.

To all whom it may concern:

Be it known that I, CHARLES J. SMITH, of Norfolk, in the county of Norfolk and State of Virginia, have invented certain new and useful Improvements in Door-Fastenings for Safety-Stoves; and I do hereby declare that the following is a full, clear, and exact description of the same, reference being had to the accompanying drawing and to the letters of reference marked thereon making part of this specification, in which—

Figure 1 is a front view of the fastener, attached to a stove-door and securing the same.

Figure 2 is a plan view of the slotted bolt-casing, detached.

Figure 3 is a plan view of the disk-plate, detached.

My present invention is an improvement on the fastening for safety-stoves, embraced in and which is distinctly covered by the second claim of my patent of June 29, 1869.

The fastening, as claimed in the patent referred to, consists in cutting a slot in the casing or shield in which the bolt works, and providing the bolt with a swinging weighted handle, the same being so arranged that after the bolt has been inserted in the cap or staple, the weighted handle, by its own gravity, falls. The bolt can only be withdrawn or returned to the casing by bringing the handle on a line with the slot in the casing.

My present invention consists in securing to the casing or shield a circular plate or disk, which, like the casing, is also slotted. This disk or plate is so pivoted as to turn freely, and is secured at such position on the casing as to prevent all lateral movement of the handle of the bolt, except when the plate or disk is so turned as to bring its slot directly on a line with the slot of the casing, when, by lifting the handle so as to enter the slots, the bolt can be drawn back.

To enable others skilled in the art to make and use my invention, I will now proceed to describe its construction and operation.

A represents a section of a safety-stove, designed chiefly for railroad cars, steamboats, &c. To the stove is hinged, in the usual manner, the door A'.

B represents the ordinary casing or shield-attachment, in which works the bolt C. This casing is slotted at b.

C is the bolt, and has secured to it a handle, D. This handle D is provided with a weighted knob, d, which causes it to fall, by its own gravity, so soon as the bolt C has been secured in the staple or cap B'.

E is a circular metal plate or disk, and is pivoted to the casing or shield at e.

This disk or plate E is provided with a slot, E'. The dimensions of this slot, like the slot b of the casing, are such as to allow of the free movement of the handle therein when it is desired to withdraw the bolt.

The operation is as follows:

The door being fastened, by the bolt C having been pushed into the staple or cap B', as clearly shown in fig. 1, the disk or plate E is then turned or falls, since it also may be weighted, to the position shown in fig. 1.

To withdraw the bolt, in order to open the door, you have simply to turn the disk or plate E until the slot E' is brought immediately over the slot b, when the handle, being lifted on a line with the slots, can readily be pushed laterally, which will return the bolt, withdrawing the same entirely from the cap or staple B'.

Having thus fully described my invention,

What I claim therein as new, and desire to secure by Letters Patent of the United States, is—

The combination of the slotted plate or disk E with the sliding bolt and swinging weighted lever or handle D, as described.

In testimony whereof I have signed my name to this specification in the presence of two subscribing witnesses.

C. J. SMITH.
